UNITED STATES PATENT OFFICE.

EMORY SUDLER AND CHARLES E. SUDLER, OF NEW YORK, N. Y.

LIQUID-DISPENSING APPARATUS.

1,404,492.

Specification of Letters Patent. Patented Jan. 24, 1922.

Application filed March 19, 1920. Serial No. 367,045.

To all whom it may concern:

Be it known that we, EMORY SUDLER and CHARLES E. SUDLER, citizens of the United States, residing at New York, in the county of New York and State of New York, have invented certain new and useful Improvements in Liquid-Dispensing Apparatus, of which the following is a specification.

This invention relates to liquid dispensing systems and has especial reference to gasoline service stands for conducting gasoline directly from a source of supply to vehicles, such as automobiles.

Objects of our invention are to provide a system for supplying gasoline to vehicles, etc., in a facile and expeditious manner; and to fully expel the gasoline from the dispensing hose thereby preventing dripping and the possibility of the purchaser not receiving full measure.

The above principal objects and numerous other co-ordinate objects, which will be apparent from the following specification, are attained primarily through the instrumentality of compressed air controlled by a multi-ported valve. In this way the apparatus is caused to function without the use of air power machines, gravity operated machines, etc. Moreover, the mechanism is simple and neither physical or mental effort of the operator will be necessary, for accurate operation of this device.

The above and other objects and advantages of this invention will be in part described and in part understood from the following description of the present preferred embodiment, the same being illustrated in the accompanying drawings, in which:

Figure 1 is a front elevational view of a dispensing stand constructed in accordance with our invention.

Figure 2 is a fragmentary longitudinal sectional view of the same showing the device in connection with a working tank,

Figure 3 is a horizontal sectional view of the valve used in this invention, one position of the valve being shown,

Figure 4 is a fragmentary horizontal sectional view of the valve used in our invention and showing a different position of the same, from that shown in Figure 3.

Figure 5 is a similar view showing still another position of the valve.

Figure 6 is a top plan view of the valve with its cap removed,

Figure 7 is a vertical sectional view

through the valve casing showing one position of the plug valve in side elevation, and illustrating the valve bearing hanger,

Figure 8 is a vertical sectional view of the 60 casing taken on the line 14—14 of Fig. 3 showing the valve removed,

Figure 9 is a similar view of the casing equipped with the valve, and

Figure 10 is a side elevational view of the 65 valve per se.

In the drawings, a dispensing stand generally designated 12 is provided which consists of a base 13, of any desired shape and material, which has upstanding thereon a 70 measuring receptacle 14. The receptacle 14 may be made of transparent material or else provided with a graduated transparent panel (not shown). Superimposed on the receptacle 14 is a casing 15.

Subjacent the stand 12 is a working tank 16 which has leading thereinto a supply pipe 17, the latter being equipped with a non-return valve 18 of any suitable design. The working tank 16 has a liquid pipe 19 80 leading upwardly therefrom through the base 13 and terminates in a valve casing 20. It will be observed that the supply pipe extends into the working tank preferably to a point in close proximity to the bottom thereof. A vent pipe 21 likewise communicates with the working tank 16, extends upwardly through the base 13 and also enters the valve casing 20.

The casing 20 may be of any desired shape 90 and size and may have mounted therein any suitable type of multi-ported valve. In the present instance, however, the valve casing is of a configuration designed to receive a plug valve 22. This valve has portions of 95 its periphery removed to provide a multi-ported structure which communicates with ports in the valve casing, as shown to advantage in Figures 3, 4, 5 and 6, and as will now be explained. Depending from the 100 valve 22 through the bottom of the casing 20 is a pintle 23, which is engaged by a suitable handle 24, the latter facilitating as a means for rotating the valve. The pintle extends below the handle and engages a bearing arranged on a yielding cross head 23'. In the position which the valve occupies in Fig. 3, the vent pipe 21 is open so that air held in the working tank 16 may be exhausted into an L-shaped passageway 26. 110 The exhaust first enters the base 26 of the passageway pursuant to which it flows

through the main leg and then into a vent pipe 31. Consequently, gasoline or other liquid in passing through the supply pipe 17 into the working tank 16 will cause air 5 in the latter to be forced through the vent pipe 21 and ultimately through the pipe 31. The compressed air supply, which is connected with the valve by a pipe 28, is cut off while the valve is in this position as is also communication from the discharge port 29. The latter is adapted for communication with a port 30 in the valve.

Figure 4 shows the second cycle of operation of the valve in which position the compressed air pipe 28 is placed in direct communication with the vent pipe 21 through the port 26. Consequently, the liquid in the tank 16 will be forced upwardly through the pipe 19 into the port 30 and through the 20 discharge port 29 to the measuring tank 14. A vent pipe 31 which communicates with the top of the measuring tank 14 is in communication with a valve port indicated at 32. The pipe 27 communicates with a passageway 37 thereby permitting the air to be exhausted from the measuring tank while the latter is being filled.

The next cycle of operation of the valve, as shown in Fig. 5, is produced by another 30 turn of the handle 24 in which position the measuring tank is placed in direct communication with the source of air supply by connecting pipes 28 and 27 through a port 33 in the valve. The air flows from the pipe 27 35 into a passageway 37 in the top of the measuring tank and thence impinges a float 35 in the measuring receptacle. The liquid will in this way be forced from the measuring tank through the discharge port 29 40 into the valve port 30 and thence through the discharge nozzle 34. During this cycle of operation the working tank 16 is vented through the pipe 21, port 32 and vent pipe 31 permitting the working tank to receive 45 a supply of liquid simultaneously with the dispensing of the contents of the measuring chamber.

After the valve is successively operated through the cycles of movement above 50 enumerated the handle 24 is returned to the position shown in Figure 3; successive operations of the device may be conducted in this way.

The float 35 is movably mounted in the 55 measuring tank 14 and is guided in its movement by the pipes 27 and 31 which extend through suitable openings in the float. A rack bar 36 extends upwardly from said float and into the casing 15. The bottom of 60 the casing serves as the top of the receptacle 14 and is provided with the passage-way 37 which communicates with the vent tube 27. Consequently when the measuring tank has been filled, and the float is in its uppermost 65 position, communication through the pas-

sage-way 37 will be closed, thereby preventing liquid from flowing thereinto.

In operation assuming the valve to be in the position shown in Fig. 3 of the drawings, in which position the float 35 is in the bottom of the measuring tank closing communication through the opening 29. Furthermore, while in this position the air in the working tank will be exhausted, in a manner heretofore set forth and the working tank permitted to fill with gasoline. The handle 24 is then operated in one direction so as to rotate the valve into the position shown in Fig. 4. In this position, the gasoline is forced from the working tank into 80 the measuring receptacle, under the influence of the compressed air which is admitted through the pipe 28. During this cycle of operation of the valve, the float 35 rises until its upper face closes the opening 85 into the passageway 37 thus preventing the passage of air and liquid therethrough. Moreover, in this way the measuring receptacle will always contain a definite amount of liquid when filled. The handle 24 is then 90 moved in the opposite direction rotating the valve into the position shown in Fig. 5, in which position, the gasoline is caused to be dispensed from the measuring receptacle through the discharge hose 34. When the 95 liquid is being discharged from the measuring receptacle, the float sinks until its lower face closes the opening 29 thus preventing the passage of any compressed air therethrough, after the measuring receptacle 100 has been emptied. After dispensing the desired quantity of gasoline from the measuring receptacle, which may or may not be the complete contents thereof, the handle 24 is returned to the position shown in Fig. 3 of 105 the drawings thereby cutting off the flow from the measuring receptacle and immediately establishing communication between the top of said measuring receptacle and the discharge hose 34 so as to permit the expansive force of the air remaining in said measuring chamber to quickly blow out the liquid contained in the discharge hose, thus 110 emptying it completely and preventing any drip therefrom.

It will be understood that the above description and accompanying drawings comprehend only the general and preferred embodiment of our invention, and that various minor changes in details of construction, 120 proportion and arrangement of parts may be made within the scope of the appended claims without sacrificing any of the advantages of our invention.

Having thus fully described our invention, what we claim as new and desire to secure by Letters Patent, is:

1. A liquid dispensing apparatus including a working tank and measuring receptacle in communication with one another, a 130

source of air supply also in communication with the tank and receptacle, a discharge hose connected with the measuring tank, and a single valve to control the filling and discharge of the tank and receptacle, one cycle of operation of the valve causing discharge of the liquid through said discharge hose, a successive operation of the valve permitting the passage of air through said discharge 10 hose for completely expelling liquid therefrom.

2. A liquid dispensing system including a measuring receptacle to receive liquid and equipped with a float operable under pressure of the liquid when the latter enters the receptacle, air conduits arranged in said re-

ceptacle and extended through the float to guide the movement of the latter, said conduits conducting air from the receptacle upon rising movement of the float, and said float being operated downwardly in the receptacle, for dispensing the liquid, under influence of air forced through said air conduits.

In testimony whereof, we affix our signatures in the presence of two witnesses.

EMORY SUDLER.
CHARLES E. SUDLER.
